UNITED STATES PATENT OFFICE.

WILLIAM S. TOTHILL, OF CHICAGO, ILLINOIS.

AMUSEMENT APPARATUS.

Application filed August 10, 1922. Serial No. 580,855.

To all whom it may concern:

Be it known that I, WILLIAM S. TOTHILL, a citizen of the United States, and a resident of Chicago, in the county of Cook and State of Illinois, have invented certain new and useful Improvements in Amusement Apparatus, of which the following is a specification, reference being had to the accompanying drawing.

10 This invention relates to improvements in that type of amusement devices wherein is provided a fixed standard that supports at its upper end a rotatable head or turntable from which load-supporting means are suspended. One example of such type of apparatus is the device shown and described in Letters Patent No. 762,959, granted to me on the 21st day of June, 1904, and commonly known as a "Giant stride." My present invention is shown in connection with a device of that character, but it is to be understood that its use is not confined to devices of that particular kind. In the device shown in said patent, and, indeed, in rotary centrally-supported amusement devices it has been common to employ anti-friction ball-bearings for the rotary head, and while such constructions have been in all respects satisfactory so far as permitting a smooth and easy rotation is concerned, it has been found more expensive to construct and maintain than is desirable. It is the object of the present invention to provide a simple and inexpensive means for connecting the rotatable head or table with the supporting standard and having the parts so constructed and arranged as to receive and hold a comparatively large amount of lubricant so as to ensure the easy turning of the head or table for a long period of time. I accomplish this object by the construction and arrangement of parts shown in the drawing and hereinafter particularly described. That which I believe to be new will be set forth in the claims.

45 In the drawing,—

Fig. 1 is a vertical central section through the upper portion of the supporting standard and the hub or central part of the rotatable head or table that is connected therewith, a small part of the hollow plug in the upper portion of the standard being broken away to show the key that holds it in place; Fig. 2 is an enlarged vertical section taken at the line 2—2 of Fig. 1; and

Fig. 3 is an enlarged cross-section taken at the line 3—3 of Fig. 1.

Referring to the several figures of the drawing,—5 indicates a standard which is adapted to be fixedly secured in place in any ordinary manner so as to hold it firmly in an upright position. Such standard, as here shown, is cylindrical in shape and best formed of a heavy piece of pipe. In its upper end is snugly fitted a comparatively long hollow plug 6 open at its upper end and the upper end portion being flanged, as indicated by 7, to adapt it to rest upon the upper end of the tubular standard 5. Through the central portion of the closed lower end of the plug 6 is a tapped opening through which is screwed a heavy bolt 8, the inner end of which is tapered to form a conical bearing for a shaft 9 whose lower end is correspondingly shaped and rests upon said bolt. As will be understood, by a turning of the bolt the position of the shaft 9 can be easily regulated, and by means of a nut 10 on the bolt the desired adjusted position can be maintained. Located within the hollow plug, but, in the construction shown, not extending the full length of such plug, is a lining member 11 in the form of a sleeve that surrounds the shaft 9 and serves as a side bearing therefor, so as to ensure a smooth rotation of the shaft and take up any side thrust thereof. By reason of the length of this sleeve bearing relatively to the length of the hollow plug, it will be seen by reference to Fig. 2 that chambers are provided in the plug both above and below said sleeve bearing, the upper chamber being indicated by 12 and the lower chamber by 13. Each of these chambers is provided for the purpose of containing lubricant material and, while the upper chamber will preferably be used for containing grease or some such semi-solid lubricant, the lower chamber will preferably be employed to contain a liquid lubricant. To conduct the liquid lubricant to the lower chamber I provide one or more passages through the wall of the hollow plug. In the construction shown these passages are two in number and extend diagonally downward from the upper end of the plug and at their lower ends end as grooves in the face of the wall of the plug. The two lubricant passages referred to are each indicated by 14. Over the upper end of the standard is a closure member 15,

which may be secured to the standard in any desired manner. It will effectually close the lubricant passages and the upper lubricant chamber, but, as shown, it will be provided with a central opening for the passage therethrough of the shaft 9. The plug is held firmly in place by a tapered key 6^a that fits a correspondingly-shaped opening in the wall of the plug.

Secured to the projecting upper end portion of the shaft 9 is the rotatable load-carrying member which, as indicated in Fig. 1, is here shown as intended for use as a "Giant-stride" apparatus, such as shown in my said Letters Patent,— the said load-carrying member having shown connected with it one of the ladder-like devices as in said patent. As before mentioned, the load-carrying rotatable member may sustain other forms of devices. The load-carrying member, as here shown, is of wheel shape, and the heavy hub portion thereof is indicated by 16 and the two spokes that are shown in the drawing, and which are bolted to the hub member, are indicated by 17. As shown, the hub member 16 is mounted centrally upon a reduced portion of the shaft 9 and rests upon the shoulder that is formed by reason of such lesser sized diameter of the upper part of the shaft. It is adapted to be secured firmly to the shaft by the impinging of a bolt 18 threaded through the hub portion 16. It of course may be secured to the shaft in any other suitable manner. With this rotatable member formed of wheel shape, it is desirable to firmly brace the several arms thereof together, and, in the construction shown, I have provided for this by the use of a heavy rod or band 19 of annular shape that lies in notches cut in the ends of these arms— see Fig. 1. The weight sustaining devices are adapted to be attached in any suitable way to the outer end portions of the arms 17, and as here shown each arm is provided with a depending hook 20 to which is secured a rope or cable 21 that carries a ladder-like device 22—the provision of these ladder-like devices enabling children to hang onto them after starting the head or table to rotating, all as fully explained in my said former patent. By the use of my invention all necessity for ball or roller bearings, in connection with a rotatable head or table member, is done away with, but by reason of the bearing of the lower end of the shaft 9 on the point of the bolt 8, and the sustaining of such shaft in a perfectly vertical manner as described, the rotation of the head or table will be as smooth and easy as if such former anti-friction devices were employed. Furthermore, by reason of the provision of the two lubricant-containing chambers within the hollow plug the shaft throughout its bearing

portions will be perfectly lubricated, and, inasmuch as such chambers are of considerable size, they will contain quantities of lubricant that will be sufficient for long periods of time.

What I claim as my invention and desire to secure by Letters Patent, is—

1. An amusement apparatus comprising in combination a hollow standard, a hollow plug in the upper end portion of said standard, a shaft projecting into said plug, a bearing carried by the plug for the lower end of the shaft, and a head secured to the upper portion of said shaft so as to rotate therewith. 70

2. An amusement apparatus comprising in combination a hollow standard, a hollow plug in the upper end portion of said standard, said plug having at its upper end a flange that rests upon the upper end of the standard, a shaft projecting into said plug, a bearing carried by the plug for the lower end of the shaft, and a head secured to the upper portion of said shaft so as to rotate therewith. 80

3. An amusement apparatus comprising in combination a hollow standard, a hollow plug secured in the upper end portion of the standard, a shaft projecting into said plug, a bearing carried by the plug for the lower end of the shaft, a sleeve-bearing within the plug and surrounding said shaft, said sleeve-bearing being of less length than the plug to provide a lubricant chamber opposite an end of the plug, and a head secured to the upper portion of said shaft so as to rotate therewith. 90

4. An amusement apparatus comprising in combination a hollow standard, a hollow plug secured in the upper end portion of the standard, a shaft projecting into said plug, a bearing carried by the plug for the lower end of the shaft, a sleeve-bearing within the plug and surrounding said shaft, said sleeve-bearing being of less length than the plug and located intermediate the ends of the plug to provide a lubricant chamber opposite each end of the plug, and a head secured to the upper portion of said shaft so as to rotate therewith. 100

5. An amusement apparatus comprising in combination a hollow standard, a hollow plug secured in the upper end portion of the standard, a shaft projecting into said plug, a bearing carried by the plug for the lower end of the shaft, said plug having a passage extending downwardly through its wall from the upper end thereof for conducting lubricant to the lower part of said plug; and a head secured to the upper portion of said shaft so as to rotate therewith. 110

6. An amusement apparatus comprising in combination a hollow standard, a hollow plug secured in the upper end portion of the standard, a shaft projecting into said

plug, a bearing carried by the plug for the lower end of the shaft, a sleeve-bearing for the shaft, said sleeve-bearing being located intermediate the ends of the plug to provide lubricant chambers in the plug opposite the upper and lower ends of said sleeve bearing, a passage through the wall of the plug from the upper end thereof for con-

ducting lubricant to the lower one of said chambers, a cap surrounding said shaft 10 over the upper end of the standard for closing said passage and also the upper one of said chambers, and a head secured to the upper portion of said shaft so as to rotate therewith.

WILLIAM S. TOTHILL.
